RESTAURANT BUILDING OR SIMILAR ARTICLE

Michael B. Manna, Cliffside Park, N. J.

Application April 9, 1956, Serial No. 40,983

Term of patent 14 years

(Cl. D13—1)

Fig. 1

Fig. 2

Fig. 3

Fig. 4

Figure 1 is a front elevational view of a restaurant building or similar article, showing my new design;

The dominant feature of my design for a restaurant building or similar article resides in the base portion thereof. The lettering disclosed in broken lines thereon is for purposes of illustration only.

I claim:

The ornamental design for a restaurant building or similar article, as shown and described.
